LOOM REPLENISHING MEANS

Edward C. Nichols, Upton, Mass., assignor to Draper Corporation, Hopedale, Mass., a corporation of Maine

Application January 7, 1955, Serial No. 480,381

8 Claims. (Cl. 139—231)

This invention relates to automatic, bobbin changing looms, and more particularly, to a bobbin transferring and revoking means associated therewith.

It is a general object of the invention to improve the reliability of the transferring mechanism to the end that faulty transfers shall be eliminated to as great an extent as practicable.

A more specific object of the invention is that of modifying the transferring and revoking means in such manner as to prevent the occurrence of anything but a normal transfer action or a complete revoking action thereby to eliminate certain undesired results which will be explained.

Other objects will appear from the following more detailed description.

According to present practice, practically all automatic, bobbin changing looms employ a shuttle feeler, frequently formed as a curved member which swings to a position in the general path of the shuttle in the forwardly moving lay, but nevertheless, in a position to just miss striking the tip of the shuttle if the latter is properly boxed. This positioning of the shuttle feeler is accompanied by a setting of a transfer mechanism actuating means which in one form comprises a latch finger and connecting members between it and a latch depresser movable with the shuttle feeler.

If the shuttle to which a full bobbin is to be transferred is improperly positioned beyond permissible limits, the tip of the shuttle will strike the point of the shuttle feeler as the lay moves forwardly and will swing that shuttle feeler to effect a revoking of the transfer function thereby to avoid the ineffective and perhaps destructive action and results likely to follow. Such mechanisms are well known and need not be described further here.

In theory, a shuttle feeler is regarded as an instrument which, failing to contact a shuttle at the transfer cycle, will permit transfer to take place, and oppositely, if it does engage the shuttle, will revoke the setting before the cycle can progress to a point where disturbance of the filling supply is started. Actually, most transfers or attempted transfers are thus carried through, but there are in-between situations where the action is not decisive and clear cut. The tip of the shuttle feeler often slips past the point of a shuttle not completely boxed and becomes arrested in some intermediate position thereon to swing the shuttle feeler as the lay moves forwardly so that instead of a revocation of complete and decisive nature, an intermediate condition prevails.

As is understood by those familiar with loom operation the point of the bunter on the lay engages a notch in the latch finger at normal transfer. If the shuttle tip due to improper boxing of the shuttle, scrapes the side of the shuttle feeler, the result may be such that the bunter tip engages more or less squarely against the top point of the latch finger. In new equipment these points are sharp enough so that they would probably slip off so that a transfer or revocation would be forthcoming; however, after extended use the points become blunt and as a result,

2

the action is one in which the bunter affects a movement of the transfer through the finger, but by contact with the point of the latter rather than with its notch. In effect, the finger or linkage is lengthened so that overtravel results if the points remain in contact, and the new or full bobbin pushes out the expended one and is itself driven down through the shuttle. Of course, the loom stops due to lack of filling as the shuttle will be picked empty.

A more serious situation develops when the members move point to point a distance sufficient to move a full bobbin from the battery and then the bunter slips over the top of the finger. In that event the full bobbin falls to and lays on the top of the shuttle; many results may be forthcoming. Frequently the movement of the lay with a shuttle thus trapped results in breaking out the front wall of the shuttle whereupon picking the shuttle may cause the warp to be torn out and/or other serious damage. Suffice it to say that in all such events some damage and lost production result, but usually the consequences are very extensive and costly.

In remediying the above mentioned trouble, the instant invention involves a somewhat standard or normal basic mechanism and instead of the usual cam for depressing the latch, a linkage functioning from the movements of the shuttle feeler to raise the latch when transfer is indicated and to depress the latch at revocation through a supplementary latch-like member hereinafter called a revoker arm and a link pivoted to it and to an arm swingable with the shuttle feeler, the relationship of the said revoker arm and latch finger being such that the bunter strikes the former first and, if below the point, in a manner to be guided to the notch in the finger. The bunter may not strike the finger point in any event as it is blanketed by the revoker arm, but may strike a similar point of the latter. In that case, and if the parts do not slip off, the pivots of the linkage are such that continued pressure merely breaks down or collapses the latch-revoker unit and no effective movement of the transfer can result.

The invention will be described in greater detail by reference to a preferred form thereof as evidenced in the accompanying figures of drawing wherein:

Fig. 1 is a view taken just outside the bobbin transfer means of a loom showing the application of the invention thereto.

Figs. 2, 3 and 4 are schematic views of a shuttle tip and shuttle feeler end illustrating possible interrelationship of these parts at bobbin transfer.

Fig. 5 is a plan view of parts which go to make up the invention.

Fig. 6 is a side elevation of the same parts shown in position to effect transfer.

Fig. 7 is a similar view, but showing revoking.

Now referring to Fig. 1, the invention is illustrated as applied to a more or less conventional fly shuttle loom in which a shuttle 10 carrying a filling package or supply 11 is adapted to be picked to and fro across a lay generally indicated by numeral 12 and carried for swinging movement on swords 13. At either end of the lay the shuttle is received in the conventional shuttle box in a manner well known to those skilled in this art and is picked to and fro across the lay by any convenient picking mechanism such as may commonly be found in these looms. The shuttle normally operates to lay the filling in the warp shed until the supply of filling carried by any particular bobbin in the shuttle is substantially exhausted whereupon feeler mechanism (not shown) comes into action to set a transfer mechanism by means of which as the lay moves forwardly, a bobbin several of which are illustrated as at B in a rotary type battery generally indicated by numeral 14, is moved from the battery to the shuttle when the parts are in alignment, at the same time

driving the expended bobbin from the shuttle. The supply of bobbins held in the battery are indexed in a clockwise direction as shown in this figure by certain mechanism including a ratchet wheel 15, stop pawl 16 and other parts not shown, and the terminal bobbin or that next to parts not shown, and the terminal bobbin 17 is positioned to be transferred shown here as the bobbin 17 is positioned against a bobbin guide 18 attached beneath a part of the hopper stand the lower portion of which indicated at 19 serves as an abutment for certain parts hereinafter to be described. A swinging bobbin guide 20 serves the usual function, the construction and operation of these batteries being well known and therefore not necessary of further description at this time.

A transerrer 21 in the form of an arm more or less horizontally disposed and having a bobbin engaging portion 22 is adapted to be swung about a transerrer stud 23 fixed in a part of the hopper stand and therefore permanently and rigidly positioned, thereby to drive the terminal bobbin such as the bobbin 17 from the position occupied in the battery to the shuttle, it being understood that the shuttle will be aligned beneath that bobbin just at that particular time. As the full bobbin is driven into the shuttle to be held in the bobbin holding springs therein, the expended bobbin will be driven out of the shuttle and down through the lay to a bobbin can or other receptacle for the purpose. The transerrer also has a more or less vertically disposed arm 24 by means of which the transerrer mechanism is caused to swing about the pivot 23 whenever the parts are properly set to be engaged by a part of the forwardly moving lay as will hereinafter be explained.

Pivoted at the point 25 on a fixed part of the loomside, or any suitable extension thereon, is a shuttle feeler 26 having a curved profile as seen in Fig. 1 and also being bent appropriately in the opposite plane so that the tip part 27 thereof may move forwardly to the dot-and-dash line position of the figure to feel or sense the presence of a shuttle tip in the event the shuttle is not properly boxed within tolerances such that one might expect a normal and effective transfer. A small amount of clearance is provided between the adjoining face of the shuttle feeler and the bobbin tip when the shuttle is completely boxed, but as is well known, shuttles rebound slightly or fail to be boxed completely, especially when the bobbin supply has been substantially exhausted, and therefore these shuttle feelers are set to permit a maximum tolerance for the shuttle position so that one may expect a satisfactory transfer. Normally the shuttle feeler is moved to the active or dot-and-dash line position by the transfer mechanism linkage as affected by the filling feeler mechanism at the opposite end of the loom.

The arm 24 has pivoted at 28 a latch stand 29 adjustably carrying a latch finger 30. The latch finger is clamped in the stand by a clamping bolt and nut 31, Figs. 5 and 6, and is maintained in an adjusted position by an adjusting screw 32 retained by lock nut 33. This latch finger is slightly modified from the usual latch finger employed in looms of this type but has its end adjacent the lay, that is, the end extending rearwardly as the finger is raised, to position its notched end illustrated at 34 for the reception of the pointed end of a bunter 35 which is in turn carried at the forward part of the lay 12.

The shuttle feeler 26 has affixed thereto an arm 36 which bends forwardly and also to the side as illustrated in Fig. 1 having at its top end a pivot or connection 37 for a link 38, the other end of this link being attached as illustrated at 39 to a second finger-like member 40 as hereinafter referred to as a revoker arm. This arm has the function of raising the latch stand and latch finger to active position to be engaged by the bunter and of lowering it to the position of Fig. 1 which is inactive. As shown in the enlarged views, arm 40 is pivoted at 41 rather high on the latch finger 30 and also has a notched end 42 the notch of which is slightly farther advanced in a direction forwardly of the loom than is the correspond-

ing notch 34 of a finger 30. This revoker arm also has a top point 43 corresponding more or less to the top point of the latch finger 30 but in a position such that the bunter 35 will strike the point 43 and not the point of the finger since the latter is shielded or blanketed off by the presence of the corresponding part of the revoker arm itself. This revoker arm also has an upwardly extending stop means 44 which engages beneath the hopper stand when the parts are in active position for transfer thus limiting the movement and also positioning the parts so that the point of the bunter may properly engage within the notch of the revoker arm. A stop pin 45 is set in a boss or other part of the latch finger 30 and limits downward movement of the revoker arm maintaining proper relationship between the two parts, a spring 46 coiled as illustrated about the fixed pivot pin 41 and having its free end 47 engaging above pin 39 in the revoker arm always serves to maintain that relationship of the parts except as shown in Fig. 7, when the revoker arm is actually employed as a part of the linkage acting to break down or collapse the latch mechanism thereby to prevent transfer as will be explained.

The link 38 is connected to the revoker arm at the pivot or pin 39 just above mentioned and against which the spring 46 bears, and to latch depressor stud 37, the latter being a more or less standard part of these mechanisms. In the usual instance such a stud is engaged by a latch depressor cam rather than being a pivot carried fixedly within the free end of an arm 36 as above described and as shown in Fig. 1. When the shuttle feeler 26 is swung to active or dot-and-dash line position in Fig. 1, the arm 36 is likewise moved throughout a corresponding angular extent and pulls upon link 38 to raise the latch finger and revoker arm to the position of Fig. 6, it being a simple matter to swing these parts about the pivot 28.

In operation, the situations illustrated in Figs. 2, 3 and 4 may be experienced. There the shuttle is shown in different positions it may occupy relative to the path of the shuttle feeler and in Fig. 2, the shuttle is shown more or less completely boxed with the feeler in position, the lay having moved forwardly with the shuttle tip clearing the feeler as intended. In Fig. 4, the shuttle has been left in a rather badly boxed position, this situation being evident whenever the shuttle does not completely enter the box or when it stops with too much residual energy and rebounds. There the shuttle feeler tip has been engaged by the shuttle point and, of course, forward movement of the lay will result in the shuttle pushing the feeler forwardly and in revocation since the forward movement or swinging of the shuttle feeler 26 results in a corresponding angular movement of the arm 36 which pushes on link 38 to swing the latch mechanism in its entirety about pivot 28 the parts thereby being returned to inactive position as illustrated in Fig. 1.

Under the first condition, Fig. 2, the forward movement of the lay results in transfer since the bunter 35 engages beneath the point of the revoker arm and even though the revoker arm is raised slightly the bunter slips downwardly and cannot escape the notch in the finger 30 so that the parts occupying more or less the position shown in Fig. 6 are pushed forwardly in a straight line movement thereby swinging arm 24 and transerrer 21 so that the transerrer tip or hammer 22 descends upon the bobbin and transfers it to the shuttle in the usual fashion.

In the situation presented in Fig. 4, the movement of the lay forwardly results in swinging the arm 36 to a position in which the latch mechanism is rendered inactive, the first angular movement of the parts being sufficient to cause a lowering of both the latch finger and the revoker arm so that the bunter 35 moves past the top of both members thereby having no effect whatsoever upon the transerrer mechanism including arms 24 and 21.

Now referring to Fig. 3, the shuttle may be left in just such a position that its point scrapes against the adjacent surface of the shuttle feeler in which event it moves the

shuttle feeler in the direction of revoking, but not sufficiently to lower the finger 30 and the revoker arm 40 so that the bunter clears them, but rather, as illustrated in Fig. 7, may cause the parts to engage at their points so that a swinging of the latch mechanism about pivot 28 is not at first apparent. It is in this situation where, if there were no second latch member or revoker arm 40, engagement of the point of the bunter with the point of latch finger 30 itself would cause the unintended operation described at an earlier part of this specification. However, with the mechanism herein described and which is to a great extent foolproof, the pressure brought by the point of bunter 35 against the top point 43 of the member 40 merely results in collapsing the latch mechanism by breaking down the linkage about pivots 28 and 41 since the parts may swing as a hinge at the latter point against the tension of the spring 46. At this point it should be noted that spring 46 has no great amount of strength and is much more easily deflected than a much larger spring coiled about the stud 23 which tends to maintain the transfer arms 21 and 24 in their raised or inactive position. Further forward movement of the lay merely collapses and swings the parts to a greater extent so that the bunter may not cause the transerrer to contact a bobbin such as the bobbin 17 and eventually the point of the bunter 35 will slip from the top of the revoker arm or, if the arm slides upwardly, there will be no pressure against the latch finger point since at that time as illustrated in Fig. 7, the action which takes place must occur entirely through the revoker arm 40 which is in effect merely a second part of the linkage which swings the latch stand and finger downwardly to the position of Fig. 1. After a certain amount of movement of the shuttle feeler or of the lay, the parts will be returned to a completely inactive position so that partial transfers or double transfers can no longer take place.

While the present description and illustrations apply by way of specific example to a replenishing and revoking means such as utilized on the well known Draper loom, it is to be understood that the invention is applicable to all such devices employed in automatic, bobbin changing looms.

While one embodiment of the invention has been disclosed, it is to be understood that the inventive concept may be carried out in a number of ways. This invention is, therefore, not to be limited to the precise details described, but is intended to embrace all variations and modifications thereof falling within the spirit of the invention and the scope of the claims.

I claim:

1. In an automatic, bobbin changing loom having a battery, a shuttle, a lay, and transerrer means for moving a bobbin from the battery to the shuttle upon call for replenishment which includes a bunter movable with the lay and means engageable and movable thereby and forming a part of a swinging bobbin transferring means, the combination of a revoking means including a shuttle feeler and means effective upon movement of said shuttle feeler by an improperly boxed shuttle for moving the means engageable by the bunter to a position in which it will be outside the path of the bunter as the lay moves forwardly in the loom, said revoking means including as a part thereof an element which when properly engaged by the bunter, will serve as a part of the linkage to effect transfer, but when improperly engaged thereby will render the device inactive and revoke the transfer setting.

2. In an automatic, bobbin changing loom having a battery, a shuttle, a lay, and transerrer means for moving a bobbin from the battery to the shuttle upon call for replenishment which includes a bunter movable with the lay and means engageable and movable thereby and forming a part of a swinging bobbin transferring means, the combination of a revoking means including a shuttle feeler and means effective upon movement of said shuttle

feeler by an improperly boxed shuttle for moving the means engageable by the bunter to a position in which it will be outside the path of the bunter as the lay moves forwardly in the loom, said revoking means comprising 5 a linkage one element of which serves both as a means to impart movements from the lay and bunter to the transferring means and also to revoke the transfer setting depending upon the shuttle position.

3. In an automatic, bobbin changing loom having a 10 battery, a shuttle, a lay, and transerrer means for moving a bobbin from the battery to the shuttle upon call for replenishment which includes a bunter movable with the lay and means engageable and movable thereby and forming a part of a swinging bobbin transferring means, the 15 combination of a revoking means including a shuttle feeler and means effective upon movement of said shuttle feeler by an improperly boxed shuttle for moving the means engageable by the bunter to a position in which it will be outside the path of the bunter as the lay moves forwardly in the loom, said revoking means comprising a linkage of two members one of which when the shuttle feeler indicates a properly boxed shuttle conveys the movement of the lay and bunter to the transfer means to effect replenishment, and when the shuttle is not 20 properly boxed imparts to the said means engageable by the bunter a movement to a collapsed and inactive position.

4. In an automatic, bobbin changing loom having a 25 battery, a shuttle, a lay with a bunter, and a transerrer means for moving a bobbin from the battery to the shuttle upon call for replenishment which includes a latch stand and a notched latch finger carried in said stand and engageable by the bunter, the combination therewith of revoking means which comprises a shuttle feeler, a revoker arm pivoted to said latch finger and having a point normally positioned rearwardly and above the point in said finger, and linkage from said shuttle feeler to said revoker arm for imparting movement thereto for aligning the finger and revoker arm with the bunter upon setting the shuttle feeler at indication for transfer and for depressing the latch finger when the shuttle feeler is moved forwardly by an improperly boxed shuttle, the said revoker arm further being effective upon contact of the bunter with the point of said arm for collapsing the latch finger and revoker arm assembly thereby to prevent a transfer action.

5. In an automatic, bobbin changing loom having a 30 battery, a shuttle, a lay with a bunter, and a transerrer means for moving a bobbin from the battery to the shuttle upon call for replenishment which includes a latch stand and a notched latch finger carried in said stand and engageable by the bunter, the combination therewith of revoking means which comprises a shuttle feeler, a member pivoted to said latch finger and having a bunter engaging end normally positioned to shield the point of the notched end of said finger, and linkage from said shuttle feeler to said member for imparting movements of the feeler to the member, finger and latch stand, the disposal of pivots between said parts being such that 35 pressure of the bunter against the topmost part of the end of the member results in collapsing the latch stand to an inactive position.

6. In an automatic, bobbin changing loom having a 40 battery, a shuttle, a lay with a bunter, and a transerrer means for moving a bobbin from the battery to the shuttle upon call for replenishment which includes a latch stand and a notched latch finger carried in said stand and engageable by the bunter, the combination therewith of revoking means which comprises a shuttle feeler, a revoker arm pivoted to said latch finger and having a notched end similar to the end of the finger, but positioned to shield the point of the notched end thereof, a stop for limiting downward movement of the arm relatively to the finger, a spring for maintaining the arm against the said stop, and linkage from said

shuttle feeler to said member for imparting movements of the feeler to the member, finger and latch stand, the disposal of pivots between said parts being such that the pressure of the bunter against the topmost part of the end of the member results in collapsing the latch stand to an inactive position.

7. Mechanism as defined in claim 6 wherein said linkage from the shuttle feeler to the revoker arm comprises an arm movable with but offset from the shuttle feeler and a link pivoted to and interconnecting said arms.

8. In an automatic, bobbin changing loom having a battery, a shuttle, a lay with a bunter, and a transerrer means for moving a bobbin from the battery to the shuttle upon call for replenishment which includes a latch stand and a notched latch finger carried in said stand

5 10 15

and engageable by the bunter, the combination therewith of revoking means which comprises a shuttle feeler, a revoker arm pivoted to said latch finger and having a notched end, the notched ends of the finger and revoker arm being similarly formed with that of the arm shielding at least a part of the end of the finger so that the bunter must first contact the point of the arm rather than the point of the finger, the pivoted relationship of the latch stand, finger and arm being such that pressure of the bunter against the top point of the notched end of the arm causes the collapse of these parts thereby to revoke a setting for transfer.
